UNITED STATES PATENT OFFICE.

CHRISTIAAN TANGENBERG, OF CHICAGO, ILLINOIS, ASSIGNOR TO HIMSELF
AND WILLIS M. SHERMAN, OF SAME PLACE.

PORTABLE SCREENING FLOUR-BIN.

SPECIFICATION forming part of Letters Patent No. 413,743, dated October 29, 1889.

Application filed March 2, 1889. Serial No. 301,752. (No model.)

To all whom it may concern:

Be it known that I, CHRISTIAAN TANGENBERG, a citizen of the United States, residing at Chicago, in the county of Cook and State 5 of Illinois, have invented a new and useful Improvement in Portable Screening Flour-Bins, of which the following is a specification.

This invention relates to the construction of small-sized or portable flour holders or receptacles adapted to family use; and its object is the production of a very cheap serviceable article, wherein the flour may be securely kept and from which it may be withdrawn in varying quantities and screened as 15 it is thus withdrawn.

My improved flour-bin consists of a cylindrical vessel made of stiff paper, and is provided with the following adjunctive features, viz: a removable flanged cover, a concave 20 screen, and an agitator immediately above such screen, and a removable drawer below and receiving the screened flour from such screen, such drawer being also provided with a removable close bottom and a screen-bottom 25 which can be used where a second screening is desired. These and other features of my invention are described, and shown in the accompanying drawings, in which latter—

Figure 1 is an elevation, and Fig. 2 a central vertical section of my improved bin. Fig. 3 is a horizontal section. Fig. 4 is a longitudinal vertical section of the drawer for catching the screened flour. Fig. 5 is an enlarged detail section of a portion of the drawer, to show the manner of supporting the close and screen bottoms, and Fig. 6 shows the agitator and its shaft.

In said drawings, A represents a cylindrical vessel formed of paper and strengthened 40 at both top and bottom by interior hoops a. At the top is a removable flanged cover B, and at the bottom is a close plate C, and preferably a surrounding flange or hoop c, both the latter being permanently attached to the 45 cylinder.

At D is a dished or concaved screen resting upon the edges of the downwardly-inclined close metal rim d. This rim d is supported upon the edge of an interior hoop e. An 50 other hoop e' may be placed below the hoop e,

the primary purpose of which is to strengthen the cylinder just above the drawer-opening.

The agitator consists of wire beaters or wings F, secured to a shaft F'. The shaft passes through openings d' in the rim d, and is held against endwise movement by the metal plate d² at its inner end and the plate d³ at its outer end, both said plates being secured to the hoop e. Wire loops f encircle the ends of the shaft, and being secured to the hoop e' by nails f' support and hold the shaft vertical. As there may be some sagging or letting down by the screen, I form the wings F with bends f², by the straightening out of which bends the diameter of the agitator 65 may be slightly increased when such sagging has taken place, thereby keeping the proper relationship between the screen and the agitator.

For rotating the shaft a crank-handle G is 70 threaded into its outer end, and for purposes of strength, as well as to avoid the formation of an opening specially to receive the crank, the shaft is made of tubular metal, as indicated. The crank thus secured may be readily taken out for purposes of shipment, &c. The crank also assists in supporting the outer 75 end of the shaft, and its diameter being less than that of the shaft the latter cannot enter the opening in the wall of the bin through 80 which the crank passes, so that no special provision to prevent end-thrust is requisite. The end wires F should pass through openings in the shaft and their ends be wrapped around the latter, as indicated.

The drawer is shown at H. It is provided with a removable close bottom h, and also with a screen-bottom h', so that by taking out the close bottom the flour may be again 85 screened prior to using it. The close bottom 90 slides upon flanges i, formed by bending the metal wall forming the sides of the drawer, as shown at Fig. 5, and the screen is supported upon the metal angle-pieces j, soldered to the interior of the wall of the drawer.

I claim—

1. In a cylindrical pasteboard screening flour-bin, an agitator mounted upon a shaft provided with supports located wholly within the bin and abutting at its ends against the 95 100

- inside walls, in combination with a crank threaded into one end of the shaft and passing through an opening in the wall of the bin of less diameter than the shaft, substantially as set forth.
5. 2. In a cylindrical screening flour-bin made of pasteboard, the hoops e and e' and the plates $d^2 d^3$, in combination with the agitator-shaft, substantially as set forth.
10. 3. In a cylindrical screening pasteboard flour-bin, the agitator, the shaft whereof is supported from hoop e' , and the dished screen supported from hoop e , in combination with said hoops, substantially as set forth.
15. 4. The cylindrical screening flour-bin made of pasteboard, wherein are combined an agitator and a screen D , said screen having a metal rim d , supported upon an interior hoop e of the bin, substantially as set forth.
5. In a cylindrical screening flour-bin made 20 of pasteboard and provided with a removable drawer located in the body of the cylindrical bin, an interior hoop e' , located just above the drawer-opening, substantially as and for the purpose specified.

CHRISTIAAN TANGENBERG.
